UNITED STATES PATENT OFFICE.

RUDOLPH HOLMAN, OF CHICAGO, ILLINOIS, ASSIGNOR TO THE VORTEX MFG. CO., OF CHICAGO, ILLINOIS, A CORPORATION OF ILLINOIS.

AUTOMATIC STOCK COUNTER.

Application filed September 15, 1924. Serial No. 737,659.

This invention relates to a machine for making paper cups, dishes or containers, and more particularly to an automatic attachment associated with the container stacking mechanisms which have associated therewith a counter having a plurality of control devices connected therewith one of which is adapted to automatically stop the container blank feed device while the other 5 is adapted to automatically cause release of a clutch mechanism whereby the container stacking mechanism and the container transfer mechanism are adapted to be stopped at predetermined times depending 10 upon the adjustment at which the counter is set for the purpose of counting off selected quantities of the formed containers.

It is an object of this invention to provide an automatic stock counter mechanism 20 adapted for use in connection with container forming machines and arranged to stop blank feeding means and container stacking means after a predetermined quantity of containers have been formed.

It is also an object of this invention to provide a cup stacking machine with an automatic counter adapted to control the cup blank feeding mechanism.

It is a further object of this invention to 30 provide a cup forming machine with an automatic cup counter associated with the cup stacking attachment of the machine and adapted after a predetermined number of cups have been formed, to automatically 35 stop the operation of the cup stacking attachment.

It is furthermore an object of the invention to provide a cup or dish forming machine wherein a stacking attachment has a 40 counter associated therewith which is equipped with means adapted to operate at predetermined times and move into a position to be actuated by a plunger rod of the cup stacking attachment to automatically 45 cause stopping of the blank feed mechanism and the cup stacking attachment.

Another object of the invention is to provide a counter for a cup stacking attachment of a paper cup forming machine, said counter adapted to be set to act after the 50 forming of a predetermined quantity of cups to cause release of a trip lever connected with the operating mechanisms of the

cup stacking attachment to automatically stop the same.

It is an important object of this invention to provide a container forming machine with an automatic counter for containers with said counter arranged to count off predetermined quantities of the formed containers as they are deposited into a container stacking attachment, and furthermore, having connected therewith to be operated thereby, a plurality of governing mechanisms which control the operation of a blank feed device and of a clutch controlled device governing the operation of the container stacking attachment of the machine.

Other and further important objects of 70 this invention will be apparent from the disclosures in the specification and the accompanying drawings.

This invention (in a preferred form) is illustrated in the drawings and hereinafter 75 more fully described.

On the drawings:

Figure 1 is a fragmentary end elevation of a container forming machine equipped with an automatic counter embodying the 80 principles of this invention.

Figure 2 is an enlarged elevation of a standard counter removed from the machine and having controlling mechanisms connected therewith for governing stop 85 mechanisms controlling different parts of the machine.

Figure 3 is a sectional view taken on line 3—3 of Figure 2.

Figure 4 is an end view of the counter 90 taken on line 4—4 of Figure 2.

Figure 5 is a fragmentary sectional view taken on line 5—5 of Figure 1 with parts shown in elevation.

Figure 6 is a detailed view of the machine 95 taken on line 6—6 of Figure 1.

Figure 7 is an enlarged detail section taken on line 7—7 of Figure 1 through the blank feed mechanism and showing parts in elevation.

As shown on the drawings:

The reference numeral 1 indicates the frame of a cup or dish forming machine of any desired construction and having mounted upon the top thereof a cup blank holding magazine 2 adapted to receive a drive

through suitable connections from the machine driving mechanism which is connected to impart a drive to a bevel pinion 3 (Figure 7). The pinion 3 is in mesh with a bevel gear 4 secured on one end of a hollow shaft 5 which is journalled in a bearing frame 6 supported on the machine frame 1. A rod or shaft 7 slidably projects into the hollow shaft 5 and has a knob or handle 8 fixed on the outer end thereof. Seated within the hollow shaft 5 and contacted by the inner end of the slidable rod 7 is a coiled spring 9 which normally acts to hold the rod projected in a release position, when a locking lever 10 is raised into a released position to permit a collar 11 secured on the rod 7 to pass beneath said locking lever. Secured diametrically through the rod 7 is a drive pin 12 the ends of which project through slots 13 provided in the hollow shaft 5. When the locking lever 10 is lowered to hold the rod 7 in its driving position as illustrated in Figure 7 the spring 9 is compressed and the drive pin 12 is seated in the inner ends of the slots 13 so that the projecting ends of the pin are positioned to coat with a pin 14 secured on one end of a container blank feed reel 15 which is rotatably supported on the hollow shaft 5 within the bearing box 6. A blank feed friction pad 16 made of rubber or other suitable material is carried by the reel 15 and projects beyond the periphery thereof so as to frictionally contact a paper blank seated in the bottom of the blank holding magazine 2 to feed the blank outwardly from the magazine at a predetermined time into the machine to be formed into a cup, a dish or a container as the case may be. The further details of the blank feeding mechanisms are not illustrated or described inasmuch as they form no part of the present invention.

Mounted on the machine frame 1 is a driving shaft 17 which is connected to receive a drive from the main driving mechanisms of the machine. Mounted on the outer end of the shaft 17 is a sprocket adapted to impart a drive to a chain 18. The chain 18 is trained around a sprocket mounted on one end of a shaft 19 journalled in suitable bearings on the machine frame 1. Loosely mounted on the shaft 19 is a bevel gear 20 which is adapted to receive a drive from a suitable one point clutch unit 21 also mounted on the shaft 19. Also loosely mounted on the shaft 19 and secured to the bevel gear 20 are cams 22 and 23 as illustrated in Figure 1. The clutch unit 21 is adapted to be operated by a yoke arm 24 which is secured to the lower end of a vertical shaft 25 journalled in brackets 26 and 27 supported on the machine frame 1. Secured on the upper projecting end of the vertical shaft 25 is a bracket arm 28 having an opening or passage on the outer end

thereof. Connected to the outer end of the bracket arm 28 is a coiled spring 29 the other end of which is secured to the machine frame. Integrally formed on the bracket arm 28 is an upwardly directed bracket arm 30 having a ball or head 31 formed on the end thereof. Pivottally mounted on the upper horizontal portion of the bracket arm 30 is a fulcrumed trigger or lever 32 one end of which projects over the ball 31 while the other end has connected therewith the upper end of a latch rod 33. The latch rod 33 projects through a boss 34 formed on the bracket arm 30 and also has the lower end thereof slightly projecting through the opening in the bracket arm 28 as illustrated in Figure 6. Secured on the latch rod 33 is a collar 35 against which the lower end of a coiled spring 36 seats. The coiled spring 36 is coiled around the latch rod 33 between the boss 34 and the collar 35. The spring 36 is provided for the purpose of holding the lower end of the latch rod projected through the apertured end of the bracket arm 28 with the lower end of the latch arm 33 seated in an aperture provided in the horizontal flange of an angle bar 37 secured to the machine frame 1. Projecting upwardly through the opening in the horizontal flange of the angle bar 37 is the upper end of a stub pin 38 which contacts the lower end of the latch rod 33. The latch rod 33 when in lowered locking position acts to hold the bracket arm 28 locked in a set position against the action of the spring 29. As illustrated in Figure 1 the actuating pin 38 has the lower end thereof supported on one end of a bell crank 39 which is pivoted on the angle bar 37. Connected to the other arm of the bell crank 39 is a connecting rod 40 the other end of which is connected to one arm of another bell crank 41 which is also pivotally mounted on the angle bar 37. Connected to the second arm of the bell crank 41 is the lower end of a connecting rod or bar 42 the upper end of which is connected with the bevelled end of a trip lever 43. The trip lever 43 has one end thereof pivotally mounted on one arm of a bell crank 44 which is pivotally mounted on a bracket arm 45 which is integrally formed on a bracket 46 which has a notch therein through which the trip bar 43 projects. The trip bar also projects through a notched bracket 47.

Rigidly supported on a bracket 48 mounted on a standard 49 on the machine frame 1 are the legs 50 of a counter housing 51 to the ends of which the notched brackets 46 and 47 are secured. The counter mechanism 51 may be of any selected standard construction having sight apertures 52 in the front wall thereof through which the numbered peripheries of the indicating discs 53 are adapted to be read. As illustrated in

Figure 3 one of the counter discs 53 is illustrated with a plurality of pins 54 on one side thereof arranged in a ring at spaced intervals. The disc 53 is provided with an opening 55 into which a member 56 projects. Pivottally mounted in the counter housing 51 is a spring controlled dog or pawl 57 adapted to coact with the pins 54 on the disc to resiliently hold said disc against rotation. The disc 53 is supported within the housing on a shaft 58 one end of which projects through one end wall of the housing and has pivotally supported thereon a bell crank member comprising a long arm 59 and a short curved arm 60 (Figure 4). Pivottally supported on one end of the short bell crank arm 60 is a pawl 61 having one end of a coiled spring 62 attached thereon. The other end of the spring 62 is connected to a projection 63 formed on the bell crank 60. The pawl 61 is positioned to project into an opening 64 in the end of the counter housing 51 to actuate the first counter disk 53 in the counter housing through the pins 54. Pivottally mounted on the top of the counter housing 51 is a control trigger or dog 65 having an integral arm 66 formed thereon from which a counterweight 67 is hung. If desired the counterweight 67 may be omitted in which case the arm 66 is made heavy enough to permit the dog 65 to fall by gravity into a latching position. The counterweight 67 acts to hold one margin of the control dog 65 seated within a notch 68 provided in the upper edge of the trip arm or lever 43. A curved finger 69 is integrally formed on the lower portion of the control dog 65 and said finger 69 projects through a slot 70 into the interior of the counter housing 51 to coact with the pins 54 on the middle counter disc 53. As illustrated in Figure 2 one end of a coiled spring 71 is connected to the trip lever 43 while the other end of said spring is connected to the bracket 47 on the counter housing 51.

As illustrated in Figure 1 the control lever 10 which governs the action of the blank feed reel drive rod 7 has the free end thereof connected to the upper end of a connecting rod 72 the lower end of which is connected to one arm of the ball crank 44.

The bell crank 60 is adapted to be actuated by means of a chain or rope 73 the upper end of which is connected with the end of the long bell crank arm 59. The lower end of the chain 73 is connected to a stud 74 formed on the lower squared link 107 having the upper end thereof connected to a vertical plunger rod 75 by a pin coupling block 82. The double link rod 75—107 forms a part of a receptacle stacking attachment mounted on the machine frame for automatically stacking the receptacles as they are discharged from the receptacle forming mechanism of the machine. A spring 108 is engaged

around a rod 109 the upper end of which is pivotally connected to the long bell crank arm 59. The rod 109 slidably projects through an apertured projection 110 secured on the counter housing 51.

The cup stacking attachment comprises the plunger rod 75—107 the upper link 75 of which is mounted to slidably project through a guide sleeve 76 supported on the machine frame 1. The upper portion of the plunger rod 75 also projects upwardly through an aperture in a top plate 77 of the machine. The upper end of the plunger rod 75 is curved downwardly as indicated at 78 and has a conical pusher head 79 mounted on the end thereof in position to engage in a discharged receptacle to move the same downwardly through a rotatable ring 80 supported beneath and projecting through the table plate 77. A ring gear 83 is secured to the bottom of the ring 80. Projecting into the ring gear 83 is the upper end of a receptacle receiving tube 81 into which the receptacles are adapted to be deposited in nested relation one within the other by the action of the conical plunger head 79 when the same is operated by the reciprocating plunger rod 75—107. Connected to the lower end of the plunger rod 75 below the guide sleeve 76 is a coupler 82 adapted to coact with the bevelled end of the trip lever 43 as hereinafter described. The ring gear 83 meshes with a pinion 84 mounted on top of a rotatable shaft 85 positioned adjacent the tube 81 as illustrated in Figure 1. The lower end of the shaft 85 projects through a suitable bearing 86 supported on the machine frame. A bevelled gear 87 is secured on the lower projecting end of the shaft 85 and is positioned so that when the clutch mechanism 21 is thrown in the bevelled gear 20 will transfer a drive to the shaft 85 thereby causing rotation of the ring gear 83 and the receptacle tube 81. The tube 81 is rotated a fraction of a revolution each time a completed receptacle or cup is deposited within the tube. This arrangement is provided so that the receptacles are nested with the folded portions thereof staggered, so as to produce a stack of cups which will be straight and will not tend to bend or curve to one side when the stack of receptacles is removed from the tube 81.

A mechanism is provided for automatically delivering or transferring a formed receptacle or cup from the forming mechanism to the stacking mechanism. The delivering or transferring mechanism broadly comprises a transfer bracket 88 which is adapted to be operated by a slideable block 120 or shoe 89 movably engaged on a stationary guide bar 90. The table 77 is slotted to permit a connecting bar 111 attached to the slideable shoe 89 to be projected upwardly through the table for connection with the 125

130

transfer bracket 88. Pivots connected to the slideable shoe 89 is the upper end of a bell crank arm 91 the lower sleeve end of which is rotatably supported on a longitudinally directed shaft 92 supported in suitable bearings on the machine frame 1. Integrally connected with the lower end of the bell crank arm 91 is a curved bell crank arm 93. Pivots connected to the free end 10 of the curved bell crank arm 93 is the upper end of a connecting rod 96 the lower end of which is pivotally connected to the end of the long arm of a bell crank 97 which is pivotally engaged on a shaft 98 supported 15 by the bracket 26 and by a bracket 99 mounted upon the bearing bracket 86 as illustrated in Fig. 1. Rotatably mounted on the short arm of the bell crank 97 is a roller 100 which is adapted to track on the periphery of the cam 22 to receive a drive from the shaft 19 when the clutch 21 is in operating position.

Tracking on the periphery of the cam 23 is a roller 101 which is rotatably mounted 25 on the end of an arm 102 the hub of which is secured to the shaft 98 adjacent one side of the bearing bracket 99. Secured to the shaft 98 adjacent the other side of the bearing bracket 99 is the hub end of an 30 arm 103. Pivots connected to the outer end of the arm 103 is the lower end of a connecting rod 104, the upper end of which is pivotally connected to the end of the short arm of a bell crank 105 which is 35 pivotally supported on a shaft 106 supported on the machine frame. The end of the long arm of the bell crank 105 is pivotally connected with the lower end of the squared plunger link 107.

40 The operation is as follows:

The receptacle forming machine is adapted to be operated from any suitable source of power and is provided with suitable driving means connected to transmit a 45 drive to the bevel gears 3 and 4 of the blank feed mechanism (Figure 7). Rotation of the bevel gear 4 causes rotation of the hollow shaft 5. When the control arm 10 is in its lower locking position as illustrated in Figure 7 the shaft 7 is held in its inner 50 position compressing the spring 9 and positioning the drive pin 12 so that the projecting ends thereof coating with the pin 14 will cause rotation of the blank feed reel 55 15. As the friction pad 16 of the blank feed reel 15 moves into its uppermost position it engages a receptacle blank in the magazine 2 and feeds the blank from the magazine into the field of operation of the 60 receptacle forming mechanisms of the machine. The advanced blank is formed into a receptacle by the forming mechanisms and is ready to be discharged from the forming means and delivered to the stacking attachment of the machine.

When the clutch 21 is thrown in a drive 70 is imparted to the cam 22 and thereby to the bell crank 97 which in turn operates the connecting rod 96 and the bell crank 91-93 to cause the receptacle pusher bracket 88 to transfer the formed receptacle from the forming mechanisms into a position over the rotatable ring 80 above the receptacle receiving tube 81.

The cam 23 on the shaft 19 coating with 75 the roller 101 operates the crank arm 102 and the crank arm 103 to cause operation of the connecting rod 104 so that the bell crank 105 is operated on the shaft 106 to cause reciprocation of the link 107 and the 80 pusher rod 75 of the receptacle stacking mechanism. With the lowering of the pusher rod 75 the plunger head 79 is lowered to seat in the formed receptacle and push said receptacle from the bracket 88 through the ring 80 and into the upper end of the receptacle receiving tube 81. The 85 formed receptacles are thus stacked in nested relation one within the other in the receiving tube 81. When the clutch 21 is in driving position the bevelled gear 20 is also rotated thereby causing rotation of the shaft 85 and the pinion 84 mounted on said shaft. The pinion 84 being in mesh with the ring gear 83 (Figure 1) causes rotation of the 90 gear 83 and the receptacle receiving tube 81 each time a receptacle is delivered thereto. By partially rotating the receptacle receiving tube 81 each time a receptacle is delivered thereto the receptacles are stacked 95 so that the folded portions thereof are deposited in staggered relation, with the receptacles forming a straight stack which will not tend to bend or curve as is the case when folded receptacles are stacked 100 with the folded portions thereof deposited one above the other.

The operation of the feeding, forming and stacking mechanisms having been briefly described attention is now directed to the operation of the automatic receptacle counter mechanisms associated with the machine and operated thereby. When the clutch 21 is thrown in the cam 23 is rotated thereby 110 causing operation of the crank arms 102 and 103 and connecting rod 104 which in turn acts to operate the bell crank 105. When the bell crank 105 is operated it acts to swing the long arm of the bell crank downwardly from the position illustrated in Figure 5 115 thereby causing lowering of the link 107 and the pusher rod 75. The plunger head 79 mounted on the pusher rod 75 is thus lowered and the receptacle is delivered into the tube 81 by the plunger head 79. The 120 chain 73 is pulled by the lowering of the link 107 and actuates the arm 59 of the bell crank 60 to permit the pawl 61 to operate the first disk of the counter mechanism each 125 time a receptacle is delivered into the tube 130

81. The trip arm 43 is held retracted by the dog 65 so that the coupler 82 will not operate the trip arm 43. It will thus be seen that each time a receptacle enters the tube 5 81 that the chain 73 acts to operate the counter to cause the counter mechanisms to register the number of receptacles delivered into the tube. The receptacles are thus automatically counted and the figures appearing 10 in the eight apertures of the counter housing indicate the number of receptacles delivered into the tube 81.

To permit the stacked receptacles to be counted off in predetermined quantities 15 within the tube 81 the disc 53 of the counter mechanism is provided with the pins 54 which are arranged ten in number at equal intervals. The pins are mounted on the disc 53 which, of course, is the disc which 20 registers hundreds and has the periphery thereof positioned to be seen through the middle aperture 52 in the counter housing. By referring to Figure 3 it will be noted that the curved finger 69 of the control 25 plate 65 projects downwardly between two of the pins 54. Each time a receptacle is directed into the tube 81 the first two registering discs of the counter are operated in the standard manner and when 100 receptacles have been delivered into the tube 81 the third counter disc 53 is rotated one tenth 30 of a revolution, thereby causing the particular pin 54 in contact with the control finger 69 to swing said finger outwardly from the position shown in Figure 3 thereby causing 35 the dog 65 to swing upwardly on its pivot out of locking engagement with the trip arm 43 to release the same. With the movement of the dog 65 out of locking engagement with 40 the trip arm 43 the spring 71 (Fig. 2) acts to pull the trip arm forwardly through the notched brackets 46 and 47 to position the bevelled end of the trip arm in the path of the coupler 82 on the pusher rod 75—107. 45 The forward movement of the trip arm 43 in a direction toward the tube 81 causes operation of the bell crank 44 which in turn acts to push the connecting rod 72 upwardly thereby automatically swinging the control arm 10 about its pivot into a release position 50 out of holding contact with the collar 11 (Figure 7) on the drive rod 7 of the blank feed mechanism. With the release movement of the control arm 10 the spring 55 9 acts to push the rod 7 outwardly with respect to the hollow shaft 5 thereby causing the drive pin 12 to move out of the path of the pin 14 on the blank feed reel 15. The blank feed mechanism is thus automatically 60 stopped at a predetermined time in the counting of the receptacles as delivered into the stacking tube 81. After the hundredth receptacle has been deposited in the tube 81 and the counter has been properly operated 65 to register the number of cups delivered, a

marker, in the form of a false cup, may be inserted through the slot in the tube 81 to project from the hundredth cup. In this way the cups deposited within the tube may easily be counted off in hundreds. 70

With the upward movement of the pusher rod 75 the coupler 82 is moved into engagement with the end of the forwardly projected trip arm 43. The trip arm is thus lifted upwardly a short distance to cause a 75 pull to be exerted upon the connecting rod 42 thereby causing operation of the bell crank 41, the rod 40 and the bell crank 39. The bell crank 39 thereby causes the pin 38 to move upwardly to push the latch rod 33 80 out of locking engagement with the aperture in the horizontal flange of the angle bar 27. When this occurs the bracket arm 28 is released and the control spring 29 connected therewith acts to swing the bracket arm 28 85 to cause partial rotation of the vertical control shaft 25. Partial rotation of the shaft 25 actuates the clutch yoke 24 thereby causing the same to move the clutch 21 into release position to disconnect the drive from 90 the shaft 19 to the cams 22 and 23 and to the bevel gear 20. The operation of the receptacle transfer mechanism and the receptacle stacking mechanism is thus automatically stopped following the stopping of 95 the operation of the blank feed mechanism.

If at any time during the operation of the machine it becomes necessary or it is desired to stop the operation of the receptacle transfer mechanism and the receptacle stacking mechanism the control dog 65 may be manually lifted by the handle 66 to release the trip arm 43 thereby causing stopping of the feeding and stacking mechanisms. 100

To start the machine, the trip arm 43 is 105 first manually pushed back to be latched by the control dogs 65. The knob 8 is next pushed in to cause starting of the blank feed mechanisms after which the lever 32 is manually operated to release the latch rod 33. The arm 28 is then manually swung 110 against the resistance of the springs 29 until the latch rod 33 comes into registry with another aperture in the member 37. The clutch 21 is thus thrown in to drive the cams 115 22 and 23 and the bevel gear 20.

After a predetermined number of receptacles have been deposited in the stacking tube 81 the blank feed mechanisms associated with the blank holding magazine 2, the transfer mechanism controlled by the cam 22 and the receptacle stacking mechanism controlled by the cam 23 and the bevel gear 20, are all automatically stopped as hereinbefore described. With the control dog 65 125 coacting with the counter middle disc 53 the automatic counter affords a means whereby the receptacle stacking mechanism is adapted to be automatically stopped every time one hundred receptacles are delivered 130

into the tube 81. With the stopping of the stacking and feeding mechanisms an attendant at the machine is merely required to place a marker of any desired type within the hundredth receptacle. The cycle of operations may now be repeated by restoring the trip arm 43, and the blank feed control rod 7 before the starting lever 32 is depressed and the arm 28 is swung into operating position to be latched therein by the latch rod 33 which is adapted to be projected back into latching position into the aperture in the angle bar 37 by means of the spring 36.

15 By associating the counter control dog 65 with the counter disc indicating thousands the blank feed mechanisms, the receptacle transfer mechanisms and the receptacle stacking mechanisms, may all be automatically stopped after a thousand receptacles have been deposited in the stacking tube 81. The counter illustrated and used in connection with the present application is a counter of standard construction having 20 the control dog 65 associated therewith as hereinbefore described and having the trip bar 43 mounted thereon with suitable connections to the blank feed mechanism and to the clutch control mechanism as already 25 described.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. The combination with a receptacle 40 stacking mechanism, of a counter, a trip member mounted thereon, a driving mechanism for said receptacle stacking mechanism, control means connected with the driving mechanism and with said trip member, a reciprocating member forming part 45 of the receptacle stacking mechanism and connected to operate the counter, and means on said reciprocating member to coact with the trip member at predetermined times to 50 cause the control means to automatically interrupt said driving means to stop the operation of the receptacle stacking mechanism after a predetermined number of receptacles have been deposited in the receptacle stacking mechanism.

2. The combination with a receptacle 55 stacking mechanism, of a receptacle counting device, means for operating the receptacle stacking mechanism, a reciprocating 60 mechanism for delivering receptacles into the receptacle stacking mechanism, a coupler on said reciprocating mechanism, a trip member on said counting device positioned to be operated by said coupler to 65 cause the operation of said stacking mech-

anism to be automatically discontinued at predetermined times.

3. The combination with a receptacle 70 stacking mechanism, of a reciprocating means associated therewith for depositing receptacles into the stacking mechanism, driving means connected to operate the reciprocating means, a clutch device governing the driving means, a counter connected with the reciprocating means for automatically 75 counting the receptacles deposited in the stacking mechanism, and means associated with the counter to be automatically actuated by the reciprocating means to cause automatic operation of the clutch device to 80 stop the operation of the receptacle stacking mechanism and the reciprocating means after a predetermined quantity of receptacles has been deposited in the stacking mechanism and counted by the counter.

4. In a receptacle forming machine the combination with the receptacle stacking mechanism and the receptacle transfer mechanism thereof, of driving means therefor, a clutch governing said driving means, a reciprocating means for delivering receptacles from the transfer mechanism into the stacking mechanism, a counter connected to be actuated by the reciprocating means, a control mechanism mounted on the counter to 90 be operated thereby at predetermined times, mechanisms for connecting the clutch device with said control mechanism, and a member on said reciprocating means for actuating the control mechanism to automatically release the clutch device to cause stopping of the operation of the transfer mechanism and the receptacle stacking mechanism.

5. In a receptacle forming machine the combination with the blank feed mechanism 105 thereof, of means for controlling the operation thereof, a counter, a control dog operated thereby, a trip member on the counter connected with the blank feed control means, and means for operating the trip member 110 and the counter whereby release of the control dog will cause automatic stopping of the blank feed mechanism.

6. In a receptacle forming machine the combination with a receptacle receiving tube, 115 of a reciprocating device for delivering receptacles to the tube, driving means connected with the reciprocating device, a clutch governing said driving means, a counter connected to be operated by the reciprocating device to count the receptacles delivered to said tube, and mechanisms connected to be actuated by the counter through said reciprocating device to cause the clutch to be automatically released after a predetermined number of receptacles has been delivered to said receptacle receiving tube.

7. In a device of the class described the combination with a receptacle receiving tube, 130 of reciprocating means for delivering re-

ceptacles into the tube, a driving means connected with said reciprocating device to actuate the same, a clutch governing said driving means, a counter connected to be operated by the reciprocating device, means for governing the operation of said clutch, a trip lever mounted on said counter and connected with said clutch governing means, a control dog supported on the counter and adapted to be automatically released at predetermined times to permit the trip lever to be actuated by the reciprocating device to cause release of the clutch and automatic stopping of said reciprocating device.

15 8. In a receptacle forming machine of the class described the combination with a receptacle receiving tube, of reciprocating means for depositing receptacles therein, a counter operated by said reciprocating means for counting the receptacles delivered into the tube, and mechanisms controlled by the counter adapted to automatically govern the operation of said reciprocating means.

9. In a receptacle forming machine the combination with a receptacle receiving tube, of reciprocating means for delivering receptacles thereto, a shoe on said reciprocating means, a driving mechanism connected to operate the reciprocating means, a clutch governing the driving means, a counter connected to be operated by the reciprocating means to count the receptacles delivered into the tube, a trip lever mounted on said counter and connected with said clutch, and a control dog adapted to be operated by the counter to release said trip lever to permit the trip lever to be operated by said shoe automatically causing release of the clutch

and stopping of the reciprocating means after a predetermined quantity of receptacles 40 has been delivered to said tube.

10. The combination with a receptacle stacking mechanism, of a counter connected to be operated thereby, a spring controlled trip lever on said counter, a control dog 45 adapted to be operated by the counter for holding the trip lever in release position, a clutch governing the operation of the stacking mechanism, a release mechanism connecting said clutch with the trip lever, said counter adapted to actuate said control dog each time a predetermined quantity of receptacles delivered into the stacking mechanism has been counted by the counter to cause release of the clutch by said trip lever 50 and stopping of the stacking mechanism.

11. In a receptacle forming machine the combination with a blank holding magazine, of blank feed mechanisms connected therewith, a slidable member for governing the 60 operation of said blank feed mechanisms, a pivoted lever for holding said slidale member in driving position, a counter for counting the number of blanks delivered from said blank holding magazine by said blank 65 feed mechanisms, and control means connected with said pivoted lever adapted to be operated by the counter at predetermined times to cause automatic release of the pivoted lever and said slidale member to stop the operation of the blank feed mechanisms after a counted number of blanks has been delivered thereby.

In testimony whereof I have hereunto subscribed my name.

RUDOLPH HOLMAN.
